DESIGN FOR A HOOD FOR A POWER
MEAT CUTTER

Vincent G. Biro, Ottawa County, Ohio, assignor
to The Biro Manufacturing Company, Marble-
head, Ohio, a corporation of Ohio

Application October 19, 1945, Serial No. 123,021

Term of patent 14 years

(Cl. D55—1)

To all whom it may concern:

Be it known that I, Vincent G. Biro, a citizen of the United States and a resident of the county of Ottawa and State of Ohio, have invented a new, original, and ornamental Design for a Hood for a Power Meat Cutter, of which the following is the specification, reference being had to the accompanying drawing, forming a part thereof.

Fig. 1 is a perspective view of a hood for a power meat cutter, showing my new design. Fig. 2 is a top plan view of the hood for a power meat cutter shown in Fig. 1. Fig. 3 is a front elevational view of the hood for a power meat cutter shown in Fig. 1. Fig. 4 is a side elevational view of one side of the hood for a power meat cutter shown in Fig. 1. Fig. 5 is a rear elevational view of the hood for a power meat cutter shown in Fig. 1. Fig. 6 is a side elevational view of the hood for a power meat cutter shown in Fig. 1 opposite to that shown in Fig 4.

I claim:

The ornamental design for a hood for a power meat cutter, as shown.

VINCENT G. BIRO.
